UNITED STATES PATENT OFFICE.

JAMES H. CRARY, OF FLUSHING, NEW YORK.

INTERNAL-COMBUSTION ENGINE.

Application filed May 26, 1926. Serial No. 111,843.

This invention relates to internal combustion engines and more particularly to two-cycle engines, an object of the invention being to provide an improved arrangement of telescoping pistons with means for compressing and firing an explosive mixture between them, whereby the pistons are forced in opposite directions and are connected to the opposite crank arms on a crank shaft, so that at each explosion direct power is applied at opposite points on the crank shaft.

A further object is to provide an engine of this character with an improved arrangement of inlet and exhaust ports.

15 A further object is to provide an engine of this character with improved means whereby a spark is made between the pistons.

A further object is to provide an engine of this character embodying various novel features of construction and combinations and arrangements of parts, all of which will be more fully hereinafter described and pointed out in the claims.

In the accompanying drawings—

25 Figure 1 is a view in transverse section of my improved engine, showing the pistons in position for the intake of fuel or gas, as it is commonly known;

30 Figure 2 is a view similar to Figure 1, showing the position of the parts ready for explosion of the gas or fuel;

Figure 3 is a view in longitudinal section, on the line 3—3 of Figure 1;

35 Figure 4 is an enlarged fragmentary view in transverse section, on the line 4—4 of Figure 1.

1 represents the cylinder, and 2 the crank case of my improved engine. 3 represents the ordinary crank shaft provided with at 40 least three crank arms 4, 5 and 6, the crank arm 5 being at an angle of 180° relative to the crank arms 4 and 6 and disposed between them.

The cylinder 1 may of course be variously 45 formed and is water-jacketed, as indicated at 7, and provided with a head 8 removably secured thereon, which is so shaped as to provide a chamber or compartment 9 for a purpose which will hereinafter appear.

50 In the cylinder 1 I provide two pistons 10 and 11, the latter telescoping within the former, and the piston 10 fitting the cylinder. The piston 10 has a closed head 12 at its upper end, and the piston 11 has a head 13 intermediate its ends, the lower end of piston 10 being open and guided in suitable

extensions 14 fixed to the cylinder and projecting into the crank case. As shown the lower end of the piston has enlargements 10° working in grooves 14a of the extensions 14.

I use the terms "upper" and "lower" in the description as applied to the drawing, but it is of course to be understood that the engine may be positioned at an angle or horizontal, and I do not limit myself by the use of these terms but merely employ them for convenience of description.

15 represents the fuel or gas inlet pipes or control pipes, which may be operatively 70 connected to any source of supply and have any suitable means for controlling the flow of the gas or fuel to the crank case 2.

A passage 16 connects the crank case with the chamber 9 above referred to, and a valve 75 17 is located in this passage 16, which may be entirely closed or partially closed to control the admission of fuel from the crank case into the chamber 7 to suit conditions.

This valve 17 is illustrated in detail in Figure 4, from which it will be noted that the valve itself is in form of a cylindrical plug having a passage 20 therethrough and constructed at one end to receive dowel pins 21 on an enlargement 22.

This enlargement 22 is fixed to a shaft 23 projecting through a sleeve 24, the latter having an enlarged end 26 removably fixed to the cylinder casing and against which the enlargement 22 bears.

An operating arm 27 may be secured to the outer end of the shaft 23, and a coil spring 28 is located around the sleeve 24 and exerts an outward pressure on the arm 27 and shaft 23 to hold the enlargement 22 95 tightly against the enlargement 26 and prevent the escape of gas without exerting pressure on the valve itself.

The cylinder 1 is formed with an inlet port 18 and an outlet port 19, preferably although not essentially, in opposite sides of the cylinder, and the exhaust port being preferably slightly above the horizontal plane of the inlet port.

The piston 10 is provided in opposite sides 105 with an inlet port 29 and an outlet port 30, and the upwardly extending apron portion 31 of piston 11 is provided with an inlet port 32 and an outlet port 33, both of said ports being above the head 13 of piston 11, 110 and between said ports the head 13 is formed with an upward extension or deflector 34.

35 represents a spark plug which is carried by the head 12 of piston 10 and is connected by a pair of pivoted links 36, 37 with a binding post 38 in the wall of the cylinder. 5 These links 36 and 37 constitute electric conductors, and when the pistons are in the position for firing, as shown in Figure 2, a spark will be formed through the medium of any electric controlling mechanism desired.

10 The piston 11 is connected by a connecting rod 39 with the crank arm 5, and the piston 10 is connected by a pair of connecting rods 40 with the crank arms 4 and 6, 15 respectively.

15 The operation is as follows:

Figure 1 illustrates the positions of the pistons with the ports 32, 29 and 18 in full communication for the inlet of fuel or gas, 20 it being understood that the gas or fuel is under compression within the crank case due to the movement of the pistons in opposite directions on the firing stroke. As the pistons move toward each other they will cut 25 off both the inlet and exhaust ports and compress the charge, when the said pistons will be in the position indicated in Figure 2. The spark fires the charge and the pistons move in opposite directions. As they near 30 the extreme of their firing strokes, the ports 30, 33 and 19 will come into register to allow the exploded gases to escape, but these ports will move out of register before the inlet ports are moved into register, as will 35 be clearly understood.

By providing an engine of this type, the pistons, telescoping one within the other and moving in opposite directions through the medium of a single explosion, will impart 40 direct force to opposite cranks on the drive shaft 3, and there will be a maximum efficiency in the utilization of the units of power employed and an increase of efficiency due to the fact that the power is multiplied and 45 greater efficiency thereof had.

Various slight changes and alterations might be made in the general form of the parts described without departing from my 50 invention and hence I do not limit myself to the precise details set forth but consider myself at liberty to make such slight changes and alterations as fairly fall within the spirit and scope of the appended claims.

55 I claim:

1. The combination with a cylinder, of a pair of telescoping pistons in the cylinder, a crank case on the cylinder, a passage connecting the crank case with the head of the cylinder whereby movement of the pistons 60 away from each other functions to com-

press a charge, said cylinder having inlet and exhaust ports therein, and said pistons having inlet and exhaust ports, said ports registering during the movement of the pistons.

65 2. The combination with a cylinder, of a pair of telescoping pistons in the cylinder, the outer piston being provided at its lower end with enlargements, a crank case on the cylinder, a passage connecting the crank case with the head of the cylinder whereby movement of the pistons away from each other functions to compress a charge, said cylinder having inlet and exhaust ports therein, and said pistons having inlet and exhaust ports, said ports registering during the movement of the pistons, and grooved guides 70 extending into the crank case and receiving the enlargements of the outer piston.

75 3. The combination with a cylinder, of a pair of telescoping pistons in the cylinder, a crank case on the cylinder, a passage connecting the crank case with the head of the cylinder whereby movement of the pistons away from each other functions to compress a charge, said cylinder having inlet and exhaust ports therein, and said pistons having inlet and exhaust ports, said ports registering the movement of the pistons, and a manually operated valve controlling communication between the crank case and the head of the cylinder.

80 4. The combination with a cylinder, of a pair of telescoping pistons in the cylinder, a crank case on the cylinder, a passage connecting the crank case with the head of the cylinder whereby movement of the pistons away from each other functions to compress a charge, said cylinder having inlet and exhaust ports therein, and said pistons having inlet and exhaust ports, said ports registering during the movement of the pistons, a spark plug carried by the inner piston, and a flexible link connecting the same with a 85 source of electricity supply.

90 5. The combination with a cylinder provided with a head having a chamber, of a pair of telescoping pistons in the cylinder, a crank case on the cylinder, a valved controlled passage connecting the crank case 95 with the head of the cylinder, said cylinder having inlet and exhaust ports and said pistons having inlet and exhaust ports, said ports registering during the movement of the pistons, a spark plug carried by the inner piston, a binding post in the head of the cylinder, and jointed links, one pivoted to the spark plug and the other to the binding post.

100 JAMES H. CRARY.
